CLAIM

We claim the ornamental design for a terminal board, as shown and described.

DESCRIPTION

FIG. 1 is a front perspective view from above of the claimed terminal board;

FIG. 2 is a top view of the claimed design of FIG. 1;

FIG. 3 is a bottom view of the claimed design of FIG. 1;

FIG. 4 is a left side view of the claimed design of FIG. 1;

FIG. 5 is a right side view of the claimed design of FIG. 1;

FIG. 6 is a rear view of the claimed design of FIG. 1; and,

FIG. 7 is a front view of the claimed design of FIG. 1.

The broken lines shown represent portions of the terminal board that form no part of the claimed design.
